UNITED STATES PATENT OFFICE.

THOMAS ELLIOTT, OF BIRMINGHAM, ALABAMA, ASSIGNOR TO CONTINENTAL GIN COMPANY, A CORPORATION OF DELAWARE.

STEEL-BOUND PRESS FOR BALING COTTON.

Application filed May 6, 1927. Serial No. 189,339.

My invention relates to a press for baling cotton, and comprises improvements in construction and arrangements of parts which are applicable both for single and double box presses.

One important object of my invention is to devise a press, the frame-work of which shall be formed of structural steel in such manner that it is simple of construction, of 10 very great and rugged strength, and is inherently braced against the strains and stresses which have heretofore required constant adjustment of parts of the present presses in order to hold the frame in alignment.

More particularly, my invention contemplates the connecting of the pairs of channel irons forming the upper and lower platens at their corresponding ends with a vertical 20 channel iron adapted to both space the channels of each platen and to rigidly connect the platens against vertical and angular transverse stresses, thus permitting a structural steel bound press frame to be provided 25 of unusual strength and rigidity and yet capable of economical manufacture.

A further object of my invention, as applied to double box presses, relates to the manner in which the strain member upon 30 which the press revolves is connected to the top and bottom platen channels. According to my invention I use a square bar rigidly bolted between cross channels interposed between the channel units of each top 35 and bottom channel and I mount on the square bar on suitable supporting plates anti-friction bearings for the rotating double press boxes.

My invention is further concerned with 40 simplifying and perfecting the counter-balancing of the press box doors, which are so heavy that they must be counter-balanced to enable one man to handle them. Heretofore, they have been counter-balanced by 45 a counterweight supported by a rope or cable passing over a pulley mounted on a superstructure above the press. According to my present invention the doors are mounted on pivot crank shafts with counterweights suspended from the crank below 50 the platform where they are free to rise and fall without interfering with the operation of the press.

Another feature of my invention relates 55 to the manner in which the side and end

doors are wedgedly engaged and clamped in operating position, and to this end I provide the press box doors near their upper free corners with co-acting wedges so disposed and designed as to stop any uplift of the end doors and to permit the side doors to open out easily notwithstanding the doors are subjected to great internal pressure. By this arrangement the effect of the outward pressure on the end doors will not tend to 60 lock the side doors, as is the case where the coacting end and side door clamps have a nonwedging engagement, but will on the contrary make it easy for the side doors to be opened out notwithstanding high internal 65 pressure on the wedge lock elements.

My invention also comprises certain details for the design of the pivot crank shaft for the side doors and the manner of mounting same in structural supports extending 70 transversely across the ends of the press box.

My invention also comprises the novel details of construction and arrangements of parts, which, in their preferred embodiment 75 only are illustrated in the accompanying drawings which form part of this specification, and in which:

Fig. 1 is front elevation of a double box press with structural strain members connecting the platens.

Fig. 2 is an end view of Fig. 1 with the side doors shown opened out in dotted position.

Fig. 3 is a cross-sectional view taken 90 through the door wedge lock members of a single box press with the channel strain members at both ends of the box.

Fig. 4 is a detail cross-sectional view taken 95 on the line IV—IV of Fig. 1.

Fig. 5 is a view similar to Fig. 4 with the door shown in open position.

Fig. 6 is an enlarged view partly broken away of the pivotal crank shaft for the doors.

Fig. 7 is a cross-sectional view on a reduced scale taken on the line VII—VII of Fig. 6.

Fig. 8 is a detail view of the main bearing for supporting the rotating press 105 boxes.

Fig. 9 is a detail end view broken away 110 illustrating a channel strain and spreader connection between both ends of the top and bottom platens of the press.

Similar reference numerals refer to similar parts throughout the drawings.

In the embodiment of my invention illustrated in Figs. 1 and 2, I have shown the 5 double box type of press, but it is to be understood that for single box presses the strain members connecting both ends of the upper and lower platens will be alike, as indicated in Fig. 3. In the drawings, the

10 revolving boxes 10 and 11 are of any standard structure and are adapted to rotate on antifriction bearings 12 that are mounted on a square center strain bar 13 which connects one end of the upper and lower platens

15 preferably by being bolted to the centers of cross channel members 14 (see Fig. 1), which serve as spreaders and have their flanges 15 connected by bolts 16 to the channels 17 forming the lower platen and to the channels

20 18 forming the upper platen. The strain bar is preferably square to facilitate its bolting between the channel members 14 at each end, and in order to support the anti-friction bearing 12 thereon I bolt supporting

25 plates or lugs 19 to opposite sides of the strain bar by cross bolts, thus providing cheap and simple mounting for the anti-friction or ball bearing support for the revolving boxes.

30 The plunger element 20 is suitably mounted between the lower platen channels 17, and the tapered bottom platens at their other ends are spaced, cross braced and rigidly connected by a single strain member formed

35 by the channel 21 (see Fig. 9), having a width suitable to space the platen members and to have its side flanges directly bolted thereto at each side. A web plate 22 can also be provided at each joint to brace this

40 spacer channel which affords an extremely simple and sturdy connection which will prevent displacement of the platens. This construction will be provided at both ends of the platens in the case of single box

45 presses, as shown by the channels 21, 21^a in Fig. 3.

The upper boxes comprise side doors 23 and end doors 24 which may be of any standard design, the end doors engaging a fixed 50 bottom rail formed by a channel 25 which extends beyond the sides of the press box. The side doors are each provided with top and bottom side door rails, each bottom rail being made up of spaced angles 26 which

55 are bolted to the side door and receive between them and are bolted to a square bar 27 which serves as pivot and projects beyond the ends of the box and passes through suitable openings provided in the end door rails

60 25 (see Fig. 6). The opening for this shaft 27 in one rail 25 is made large enough to receive a cylindrical bearing end 28 on a casting 29 which has a horizontal groove extending part way through one face to

65 snugly receive the adjacent square end of

the shaft 27. This casting is adapted to receive the tie bolts 30 which pass therethrough on each side of the shaft 27 and engage the loop end of a crank bar 31, and hold it rigidly clamped to the shaft 27 so 70 as to turn therewith. Each crank bar 31 at its lower end is pivotally connected by a pair of links 32 to the center of an elongated counterweight 33 which hangs between the platform 34 and the lower structural 75 members 35 connecting the bottom of the boxes 10 and 11. These weights are also preferably arranged between the boxes in the double box press and therefore, as seen in Fig. 1, the castings 29 are arranged for 80 each side door adjacent to the center strain bar 13. The crank bars are sufficiently bent to offset the several weights so that each will move independently of the other and in order that the weights may take up but little 85 space vertically they are substantially elongated as shown more clearly in Fig. 2. In order to increase the bearing surface for the bearings 28 of the square ends of the shafts 27, I may weld a bearing collar 36 to each 90 adjacent channel rail 25. The other ends 37 of the shafts 27 are turned and mounted to rotate in a bearing formed partly in the adjacent rail 25 and in a sleeve 36 welded to 95 said rail.

Each press box has one side door provided with a top rail formed by a pair of spaced channels 38 between which are mounted bearings 38^a suitably bolted or otherwise attached thereto. These form the inner 100 bearings for the upper end of the lock bars 39 which extend beyond the ends of these rails and are provided with cam ends 40 adapted to engage the eye 41 at the free end of each stirrup 42, these stirrups being adjustably connected at their other ends to spacer wedge blocks 43 mounted between the overhung ends of the angles 38^a forming the top rail of the other side door of the 105 same box.

The channels 38 project beyond the ends of the press box and there receive spacing wedge blocks 44 which are grooved to serve as outer bearings for the lock bar 39. The blocks 43 and 44 are adapted to co-act with the shouldered wedge plates 45 that are bolted to the channels 46 which form the upper rail for each end door, the blocks 43 and 44 on each side door being arranged to engage between them the adjacent wedge plates 45 at each end of the press box. The shoulder 45^a on each wedge plate will engage the co-acting block 43 or 44 and hold the end door against lifting responsive to internal pressure. As a result of this construction, notwithstanding very high internal pressure acting on the end doors, the wedge interlock permits the easy outward opening of the side doors.

The lock bars 39 carry latches 47 adapted

to engage detents 48 on the lower cross rail of the side doors and the under channels 38 of the upper rails on the side doors have blocks 49 attached thereto which will serve 5 as legs to support the side doors when fully opened out.

The press boxes have brackets 50 attached to their rails and the brackets carry an upper bearing 51 on the strain bar 13.

Having constructed the press in the manner described, it will be obvious that the side doors can be readily opened out without being jammed to the end doors because of the internal pressure, and that one man can easily handle them, due to the effective manner in which they are counter-balanced by the weights 33. Due to the almost complete employment of structural metal in the binding of the press boxes and in the bracing of the platens, I obtain what I term a steel bound press which requires no adjustment of its strain members, which will rigidly hold the platens in correct alignment and in fixed relative position, notwithstanding the excessive strains to which the press is subjected in service, and which will possess an exceedingly durable and rugged press structure.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. A press of the character described, comprising end doors, side doors, wedge members

mounted to project beyond the side doors at each end near the top, and co-acting wedge members mounted at each side near the top of the end doors, said wedge members being disposed when engaged to interlock in planes 45 divergent from the side doors towards the transverse center line of the press box.

2. A press according to claim 1, in which the side doors having hinge mountings, and the wedge member on the end doors is shouldered to engage under the co-acting side door wedge and adapted to hold the end door against rising.

3. A press of the character described, comprising side doors, means for pivotally mounting the side doors having a crank connected to each pivot means, and a counter-weight suspended from the crank.

4. A press according to claim 3, in which the pivotal mounting means for each side door embodies a square bar having a cast bearing fast on one end, a crank rigidly connected to said casting, and a weight pivotally suspended by links from said crank.

5. A press of the character described, comprising side and end doors, a bottom rail for each end door formed by a channel projecting beyond the side doors, the side doors having bottom rails comprising a square bar bolted between angles attached to the door and journaled in said channels, bearings mounted on one end of each square bar and adapted to turn in said channels, each of said bearings having a square recess to receive the square bar, means to clamp a crank to each bearing so as to underhang from the bar, and a counter-weight pivotally connected by links to each crank.

In testimony whereof I affix my signature.
THOMAS ELLIOTT.
